United States Patent Office

Des. 221,451
Patented Aug. 17, 1971

221,451

NOVELTY PISTOL

Marvin C. Hewett, 5273 Independence Road,
Boulder, Colo. 80302

Filed Mar. 10, 1970, Ser. No. 21,838

Term of patent 7 years

Int. Cl. D21—01

U.S. Cl. D34—15

FIG. 1

FIG. 2

FIG. 3

FIG. 1 is an elevational side view of a novelty pistol showing my new design, the opposite side of the device being a mirror image of the side shown.

FIG. 2 is an elevational view of the left end of the novelty pistol shown in FIG. 1.

FIG. 3 is an elevational view of the right end of the pistol shown in FIG. 1.

I claim:

The ornamental design for a novelty pistol, substantially as shown and described.
